UNITED STATES PATENT OFFICE

JAMES J. TAYLOR, OF WYOMING, OHIO, ASSIGNOR TO THE STACEY BROS. GAS CONSTRUCTION COMPANY, OF ST. BERNARD, OHIO, A CORPORATION OF OHIO

RIVETER

Application filed November 27, 1928. Serial No. 322,228.

This invention relates to improvements in riveters particularly adaptable for riveting plates in the erection of tanks or holders, the riveter travelling upon the upper edge 5 of the plates being riveted and yoked thereabout, sustaining a centered hammer and dolly at relatively opposite sides of the plates, with the hammer controllable preferably from the dolly side, enabling a single operator to place and head the rivets.

An object of the invention is to provide a transportable riveter carrying a dolly and hammer in centered opposing relation, capable of control by a single operator for 15 placing and heading the rivets.

Another object of the invention is to sustain a dolly and a pneumatic riveter hammer in opposing centered relation, the hammer provided with a clamping head for compressing 20 together the parts to be riveted and against the dolly, the clamping head controlled with the control of the hammer.

Further objects and advantages will be more fully set forth in a description of the 25 accompanying drawings, forming a part of this specification, in which:

Figure 1 is a side elevation of the improved riveter shown as mounted and tracked upon the upper end of a steel plate, 30 with the plate in position to be riveted to a second plate below.

Figure 2 is an end elevation from the dolly side.

Figure 3 is a section on line 3—3, Figure 1. 35 Figure 4 is a section on line 4—4, Figure 1.

Figure 5 is a detail side elevation of the clamping head which is capped over the hammer end.

Figure 6 is a section on line 6—6, Figure 1.

Figure 7 is a section on line 7—7, Figure 1.

Figure 8 is a sectional view through the hammer cylinder.

As the riveter is particularly adaptable for riveting together sheet metal plates used in the erection of large circular tanks or holders, it is shown in such capacity mounted and tracked upon the upper edge of a 45 vertical plate superposed upon a second 50

plate, and capable of being tilted or swung for riveting along a vertical seam of the plates.

The riveter thus can be conveyed or 55 shifted upon the plates, as a track, as the riveting progresses about the holder or tank, with the dolly and hammer moving as a unit at relatively opposite sides of the plate or seam and relatively centered and in line with the rivet holes in a circular row, or 60 can be tilted for staggered riveting or riveting along a vertical seam.

The rivets are inserted and headed, one 65 after another, by a single operator, with the control of the hammer from the dolly side, 70 from which side the rivets are inserted, materially reducing the labor cost. The rivets are more uniformly compressed and headed with the dolly and hammer relatively centered, insuring a more efficient sealing joint 75 or seam and also facilitates the riveting operations under increased capacity.

With the operator positioned on the dolly 75 side, the side at which the rivets are inserted, he is in position to head a rivet as soon as he has the dolly positioned over the rivet.

The riveter is provided with means for initially clamping the plates together at the seam and against the stationary dolly by a 80 movable clamp head at the forward end of the pneumatic hammer, controlled with the control of the hammer.

The riveter comprises a yoke frame preferably formed of a pair of parallel stanchions 1—1 engaged through and secured to a cross head 3, the stanchions and head thus combined, representing a U form of structure to provide a work receiving throat for straddling the plates to be riveted, with 85 a hammer and dolly relatively centered and secured respectively to the opposite lower ends of the stanchions as a unit with the frame.

The stanchions preferably are engaged 90 through split eye clamps formed integral with the cross head and at relatively opposite ends thereof, each clamp provided with a bolt 5 engaged through projecting ears of the clamp for compressing the clamp and 95 100

to frictionally bind or connect the stanchions to the cross head, as well as providing means for adjustably connecting the stanchions to the cross head for varying the reach or 5 throat length of the frame.

A dolly 6 is rigidly clamped within an eye clamp 7 studded and fixed into the lower end of one of the stanchions, and a pneumatic hammer movable within a sleeve or 10 cylinder 8 clamped within an eye or sleeve clamp 9 studded into and fixed into the lower end of a second stanchion in axial alignment with the dolly, the anvil end of the dolly and the hammer being relatively 15 adjusted to accommodate for the throw or stroke of the hammer in addition to the thickness of plates and size of rivets.

The frame is adjustably mounted upon a carriage or trolley by which the riveter is 20 easily transported or conveyed, as upon the edge of the plate or other tracking facilities, for progressively moving or advancing the riveter for the rivet spacing along the seam, and is also pivotally mounted upon the carriage, adapting the frame to be tilted or 25 swung in an arc for adjusting the axis of the tools to various elevations necessary to register the tools with the axis of the rivets to be headed.

30 The carriage or trolley comprises a pair of peripherally grooved wheels 10-10 arranged in tandem between a pair of opposing side plates or bars 11-11, the wheels being relatively journaled to opposite ends 35 of the bar. A pivot block 15 is interposed between the carriage side bars 11-11 and pivotally connected thereto by a pin engaged through the block and side bars. The pivot block 15 is fixed to the underside of a 40 cross beam 12 forming a bolster for supporting the yoke frame upon the carriage.

The bolster at each of its opposite ends is provided with a pair of clamp clips 13 for engaging the stanchions and frictionally 45 clamping the bolster to the stanchions to combine the same rigidly with the yoke frame after the adjustments of the frame upon the bolster have been made for changing the length of frame throat.

50 A hanger 14 of U form is fixed centrally upon the upper side of the bolster which is engaged by a screw 16, having a threaded connection with the hanger, and the head of the screw swivelled within a clip 18 fixed 55 to the underside of the cross head 3. The screw is provided with a spanner collar or flange for rotating the same by means of a hand bar 16', the hand bar normally being locked by a U clip 16² fixed to one of the 60 stanchions, this means serving to lock the screw against rotation when the riveter is in use. The screw provides a micrometric adjustment for the frame upon the carriage for varying the reach or throat length, in 65 addition to the adjustment or setting of the

stanchions upon the cross head. The cross head adjustment is utilized for making what is termed "coarse adjustments" while the screw is relied upon for making more delicate or finer adjustments, it being recognized 70 that the frictional bind or clamp of the arms upon the stanchions is released previous to making any vertical adjustment of the frame upon the carriage, and the parts re-clamped after an adjustment, holding the 75 parts in their set position under the heavy vibration to which the frame is subjected when the hammer is in operation.

The pneumatic hammer may represent a commercial type of riveter hammer or gun, 80 and in general comprises a barrel having a hand hold cap secured upon the rear end thereof to which the air-line or pressure connections are made, the barrel containing a reciprocating piston controlled by a valve 85 automatically operated when the air pressure is admitted into the rear end of the barrel.

To utilize the commercial hammer, its cap is removed and the barrel 24 on the rear 90 end thereof provided with a packing 25 and slidably engaged within the sleeve or cylinder 8 held within the eye clamp 9 upon the lower end of one of the stanchions 1, the barrel serving as a piston adapting the gun 95 to be bodily moved forwardly when the air pressure is admitted into the rear end of the cylinder 8 to bring the clamp head 19, fixed upon the forward end of the barrel 24, into clamping engagement with the work.

The rear end of the cylinder 8 has a closure cap or head 23 to which the line connections are permanently made, the connections being sufficiently flexible to permit of longitudinal adjustment of the cylinder 8 within its eye clamp 9. Admitting air into the rear end of the cylinder and into the chamber formed by the cap and rear end of the barrel, immediately forces the barrel and its contained mechanism as a unit forwardly, 100 and is held in such forward position as long as the air pressure is maintained against the end of the barrel, the end of the barrel being ported for supplying the pressure to the operating mechanism within the barrel for 105 hammer reciprocation.

Thus, the gun has twofold function; that of supplying a clamp for the work, and a reciprocating hammer for heading the rivet of single control, so that the gun is always in 110 position for its clamping utility during the operation of the hammer.

The eye clamp 9 has a stirrup 20 extending from its rear end centrally, straddling the cylinder 8, with its cross bar 21 provided with a screw 22 bearing against the cylinder cap or head 26 for micrometrically adjusting the cylinder and riveter gun relative to 120 and from the dolly 6.

The line of pipe for supplying the pres- 125

sure fluid connects with the hammer tapping into the rear end of the hammer casing and extends about the frame from one side to the opposite side, so as to bring the control to the dolly side. The pressure to the hammer may be controlled by any type of control valve stationed in the line as indicated at 4, the valve merely admitting or cutting off the pressure fluid to the hammer.

10 The piping is preferably clamped or rigidly fixed to the frame by means of clamp clips 23 and the connection with the end of the cylinder sufficiently flexible to allow for the necessary longitudinal adjustment of 15 the cylinder within the eye clamp. This, however, may be modified or other methods employed for service line connections and pressure control.

As shown, the dolly is of two-part form, 20 comprising a stock portion secured within the eye clamp 7 and a removable anvil engaged into an end of the stock for anvil substitution, different shapes being utilized for various sizes of rivets. In erecting the 25 tank, the plates are temporarily assembled and bolted together, giving the same sufficient rigidity for sustaining the necessary 30 rigging and riveter, the carriage of the riveter engaged on the uppermost plates, bringing the riveting tools at relatively opposite sides of the seam to be riveted.

The throat or reach of the frame is adjusted to bring the tools to the proper elevation, aligned with a horizontal row of the 35 rivet holes, whereupon it is in position for operation. The operator stationed at the dolly side inserts a rivet, after which the frame is moved to bring the anvil of the dolly over the head of the rivet, whereupon 40 the control valve is operated, admitting the pressure into the rear end of the cylinder moving the gun forwardly for the clamping feature and operating the hammer.

The clamp head 19 connected upon the 45 hammer valve with the forward movement thereof is brought against the seam of the plates, pressing the plates and forcing the same against the anvil about a rivet hole. This clamping pressure is maintained for 50 the full operating period of the hammer and released in cutting off the pressure to the hammer.

For staggered riveting, the riveter preferably is adjusted to bring the tools in line with a lowermost row of rivet holes and the frame is tilted upon the carriage to reach those holes at a higher elevation. The frame, likewise, is tilted upon the carriage 60 for riveting along a vertical seam of the plates.

Having described my invention, I claim:

In a riveter, a carriage constructed for travelling upon an edge of the plates to be riveted, a bolster pivotally mounted upon

the carriage, a yoke frame for straddling the plates adjustably mounted upon the bolster, and centered relatively opposing riveter tools mounted upon said frame for operating upon opposite sides of the plates. 70

In witness whereof, I hereunto subscribe my name.

JAMES J. TAYLOR.
